Hupp

[11] Patent Number: Des. 379,359

[45] Date of Patent: **May 20, 1997

[54] **MOLD FOR FORMING CONCRETE
HEXAGONAL STEPPING STONES**

2,345,707 4/1944 Leising 249/117

[76] Inventor: **Jack T. Hupp, P.O. Box 1206,
Richmond, Tex. 77469**

Primary Examiner—Antoine Duval Davis
Attorney, Agent, or Firm—Kenneth A. Roddy

[**] Term: **14 Years**

[57] **CLAIM**

[21] Appl. No.: **51,632**

The ornamental design for a mold for forming concrete
hexagonal stepping stones, as shown and described.

[22] Filed: **Mar. 14, 1996**

DESCRIPTION

[51] LOC (6) Cl. **15-09**

FIG. 1 is a top perspective view of a mold for forming
concrete hexagonal stepping stones showing my new design
from the top and one side;

[52] U.S. Cl. **D15/136**

FIG. 2 is a bottom perspective view thereof showing my new
design from the bottom and the side opposite that shown in
FIG. 1; and,
